UNITED STATES PATENT OFFICE.

ERNEST J. CRAWFORD, OF CAMPBELL, CALIFORNIA.

PUMP FOR GASOLENE-GAS MACHINES.

SPECIFICATION forming part of Letters Patent No. 634,612, dated October 10, 1899.

Application filed May 20, 1898. Serial No. 681,181. (No model.)

To all whom it may concern:

Be it known that I, ERNEST J. CRAWFORD, a citizen of the United States, residing at Campbell, county of Santa Clara, State of California, have invented an Improvement in Gaso- 5 lene-Gas Machines; and I hereby declare the following to be a full, clear, and exact description of the same.

My invention relates to an apparatus which is especially designed for the manufacture of gasolene or hydrocarbon gas, the apparatus being so constructed that it may be used as a portable or stationary machine.

My invention consists, essentially, in the connection of a generator, an air-pumping mechanism, a gasometer, and a novel intermediate mechanism whereby the air-pumping device is automatically actuated to supply air, and a means for regulating the supply of air through the generator or partially through the generator and to the gasometer.

It also comprises details of construction, which will be more fully explained by reference to the accompanying drawing, in which 25 the figure is a general view of my apparatus.

A is the gasometer-tank, and B the gasometer, of any usual or suitable construction adapted to rise and fall in the tank as the supply of gas increases or decreases.

30 C is the gas-generator, of which I have shown an exterior view only, the interior being provided with any of the well-known devices for passing air through or over a body of light hydrocarbon, by which the air becomes mixed or saturated with the hydrocarbon vapor in sufficient quantity to become an illuminating gas, and from this generator the gas thus produced passes through the pipes D to the gasometer. The pipe E ad- 35 mits air into the generator and is provided with a cock e, by which the amount supplied to the generator may be regulated.

F is a pipe extending from the pipe E to the pipe D and having in it a cock f, by which the flow through this pipe may be regulated. 45 Thus if it is desired to send a whole volume of air through the generator the cock f will be closed and the cock e will be opened; but if it is desired to send only a portion of the 50 air through the generator and the remainder of it directly to the gasometer, as where the gas is too rich, the cock e will be partially

closed and the cock f proportionately opened. The body of air would then be divided and a portion (depending upon the openings of the 55 valves) would pass through the generator, while the remainder would pass directly to the gasometer and the richness of the gas can thus be regulated at any time. The gas which passes through pipe E is prevented 60 from returning by a check-valve G.

The supply for the apparatus is produced by a pump which consists of an open bottom and closed top cylinder H, formed with double walls, as shown. These double walls fit upon 65 each side of a similarly-shaped diaphragm I, which projects upwardly from the bottom of a tank J, containing water, this tank being filled to a point near the top.

An inlet-pipe K opens into the tank and 70 interior of the part H above the water-line and has an inwardly-opening valve L, through which air is admitted into the part H when the latter is raised, because by raising this part a vacuum is produced above the 75 surface of the water, which causes the air to rush in through the pipe K, and when the part H is again forced downward in its tank J the valve L will be closed and the air will be forced out through the pipe E and the 80 check-valve G, previously described.

In my invention I actuate the pump portion H by direct movement in both directions, and this is effected by a piston M reciprocating in a pressure-cylinder N and hav- 85 ing a piston-rod m extending through the top of the pressure-cylinder N and connecting with the top of the reciprocating chamber H, which forms the pump. In order to actuate the plunger M, I have shown the pipes O and 90 O', one connecting with the top and the other with the bottom of the pressure-cylinder N, and a means for alternately supplying water-pressure above and below the piston to recip- 95 rocate it.

The water-pressure is supplied in any suitable manner. I have here shown it as arriving through a pipe P, which may be connected with some sufficiently high source of supply to give the necessary head. This pipe 100 has a valve in it at P', and the valve has a lever P², the end of which is connected by a cord, chain, or other suitable connection P³ with the gasometer B. The weight P⁴ is also

connected with the end of the lever, a the operation will then be as follows: When the gasometer sinks by reason of the exhaustion of the gas, the cord P^3 will be relaxed and the weight P^4 will act to pull down on the lever P^2 , thus opening the valve at P' to allow the water-supply to pass in for the purpose of actuating the pump. As the pump operates and the amount of gas increases the gasometer B will rise and will gradually close the valve P' by its action upon the lever P^2 through the cord P^3 . In order to alternately supply the water to the pressure-cylinder N for the purpose of actuating the piston M and the air-pump, I have shown connections from the pipe F , by which the water may be diverted alternately into the pipe O and the pipe O' . At the same time the opposite side of the piston M is connected with the waste or discharge passage, so as to allow it to reciprocate. These connections consist, essentially, of three-way cocks or valves. In the present case I have shown two three-way cocks Q Q' situated in a pipe R , which is connected with the pipe P directly through one of the valves and through a branch pipe R' by means of the other valve. These valves have lever-arms S connecting with them, and the lever-arms are united by a rod or bar T , so as to move in unison. One of the arms S extends so as to be connected with a vertically-reciprocating rod U , the lower end of which is connected with a plunger in a cylinder V . The upper end of the rod is suitably guided and has upon it a weight W sufficient to move it downward when released from pressure from below, so that when the rod is moved up the valves Q Q' will be turned to admit the flow of water through one and close it from the other, and when moved downwardly the flow will be reversed. In order to produce these movements, I have shown a three-way cock a in a pipe b , which connects with the main supply-pipe P . Upon one side this cock connects through a pipe c with the bottom of the cylinder V , so that when water is admitted into this cylinder the plunger therein will be moved up by the pressure, and with it the plunger-rod U , and this carries the lever-arms S , and thus changes the valves Q and Q' . When the valve a is turned in the other direction, it closes the inlet-passage b and opens a passage through the waste-pipe d to allow the water to escape through the cylinder V , and when this is done the weight W will act to again shift the valves Q Q' . The operation of the valve a is effected by means of a lever a' , which has connected with it a rod g , and this rod extends up through a guide h , projecting from the side of the pumping-chamber H . Lugs or buttons i are fixed by set-screws at any desired position apart upon the rod g , so that when the arm h strikes either of these buttons it will move the rod g and, acting through the lever-arm a' , will operate the valve a to change the direction of the water within the pipes b c d .

The operation will then be as follows: Water being under pressure in the pipes P b c , when the air-pumping chamber H is at its lowest point it will strike the lowermost of the lugs i and will operate the lever a' , so as to turn the valve or cock a , and water will pass from the pipe b through this valve into the pipe c , thence into the cylinder V , where it will act to force the plunger upward, and by the connection between the plunger-rod U and the levers S it will turn the valves Q Q' , so that water will pass through the valve Q , thence through the pipe O' to the lower part of the pressure-cylinder N , and will thus force the piston M upward. The lowermost valve Q' will be so connected with the pipe O that water from above the piston or plunger M passing out through the pipe O through the valve Q' will enter the branch escape-pipe d' and pass out through the pipe d . When the air-forcing chamber H has reached the point where the arm h engages the uppermost of the lugs i on the rod g , the lever-arm a will be moved in the opposite direction and the valve a will be turned so as to cut off the water-pressure below the piston in the cylinder V and at the same time will open passage between the pipe c and the waste-pipe d , so that the water within the cylinder may escape. The weight W then acts to force the rod U and its plunger down again and with sufficient pressure to move the valve-actuating levers S and to change the position of the valves Q Q' , so that water will be admitted through the pipe O to the pressure-cylinder N above the piston M , and will thus force this plunger down by direct pressure. This change in the valve opens communication through the valve Q and the pipe d' with the escape of waste-pipe d , so that the water beneath the piston M will be allowed to escape. By these alternate reciprocations the air-forcing chamber H is moved in each direction by direct pressure, and its operation is thus made automatic and continuous, not depending upon gravitation for its downward movement.

Having thus described my invention, what I claim as new, and desire to secure by Letters Patent, is—

1. An apparatus of the character described comprising the combination of an air-pumping mechanism including a double-walled tank and a double-walled cylinder open at its bottom and closed at its top, with the walls of the cylinder embracing the inner wall of the tank, an air-inlet pipe within the cylinder and having an upwardly-opening valve which admits air as the cylinder rises and cuts off the flow of air as the cylinder descends, a hydraulic motor vertically disposed within the double-walled cylinder and having a stem-and-piston connection therewith, an air-pipe leading from the interior of the double-walled cylinder, a water-supply pipe, branch pipes leading from the water-supply pipe to points above and below said piston, valves in said

branch pipes and levers connected with the stems of said valves, a supplemental cylinder and a plunger-rod extending from the same and having one of the valve-levers connected therewith whereby the valves are operated in unison, a waste-pipe and a valve controlling the same, and a rod connected with the last-named valve and operated by the rising and falling of the double-walled cylinder.

10 2. The combination of a water-supply and valves controlling the same, and an air-pumping mechanism consisting of a tank having double walls forming a water-space, an open-bottom cylinder within said tank and having double walls adapted to straddle the inner wall of the tank, a vertically-disposed cylinder interior to the double-walled cylinder and connected at its upper and lower portions with the water-supply, a piston within said cylinder and having a stem or rod connected with the double-walled cylinder, and an air-pipe connecting with the interior of the tank.

15 3. In a gasoline-gas machine, an air-pumping device comprising a water-containing tank, an open-bottomed double-walled chamber, dipping into the water-tank, an interior wall to said tank extending between the double walls of the upper chamber, acting as a guide therefor, an air-pipe opening into the 20 chamber above the surface of the water having a check-valve therein, a cylinder centrally located within the air-pumping chamber having a piston movable therein, a rod

connecting it with the top of the air-forcing chamber whereby the two are movable in unison, water-pipes connecting the top and bottom of said cylinder, exterior valves by which the water is alternately led above and below the piston, a supplemental vertical cylinder exterior to the pumping mechanism, having 25 a plunger movable therein, the plunger-rod of which connects with the valves of the main cylinder; to change the course of the water alternately by the movement of the valves, a supply-pipe through which water is admitted below the plunger of the supplemental cylinder, a valve by which the water is alternately admitted and allowed to escape therefrom, a series of pipes connecting the main supply-pipe with the main and supplemental cylinders through which the water is diverted by the action of the valves, a lever connecting with the valve of the supplemental cylinder, a rod connecting the said lever extending upward by the side of the air-forcing cylinder and having adjustable lugs or stops thereon, and an arm fixed upon the pumping-chamber H adapted to engage the lugs upon the rod to open and close the supplemental cylinder-valve.

In witness whereof I have hereunto set my hand.

ERNEST J. CRAWFORD.
